FLUORESCENT FIXTURE

Edwin F. Guth, Florissant, Mo.

Application July 16, 1943, Serial No. 494,911

5 Claims. (Cl. 240—78)

This invention relates to a fluorescent fixture and more particularly to an integral fluorescent channel support for fluorescent lamps.

Among the objects of this invention may be noted the provision of an integral supporting channel for fluorescent lamps; the provision of a supporting channel of the type indicated which can be formed from a one-piece blank; the provision of a channel of the type stated which can be easily and quickly formed with relatively inexpensive equipment; and the provision of a supporting channel for fluorescent lamps which can be formed from a one-piece blank with a single action and without the use of a blank holder. Other objects will be in part apparent and in part pointed out hereinafter.

The invention accordingly comprises the elements and combinations of elements, steps and sequence of steps, features of construction and manipulation, and arrangements of parts which will be exemplified in the structures hereinafter described, and the scope of the application of which will be indicated in the following claims.

In the accompanying drawings, in which is illustrated one of various possible embodiments of the invention,

Fig. 1 is a top plan of the entire fixture;

Fig. 2 is a side elevation of the fixture;

Fig. 3 is an end elevation of the fixture;

Fig. 4 is a half section taken along line 4—4 of Fig. 1 on an enlarged scale;

Fig. 5 is a section taken along line 5—5 of Fig. 2 but likewise on an enlarged scale;

Fig. 6 is a plan of the channel blank which has been punched but not yet formed;

Fig. 7 is a bottom plan of the formed channel; and

Fig. 8 is a bottom plan of the reflector designed for use in association with the supporting channel as shown in Figs. 1—5.

Similar numerals indicate corresponding parts throughout the various views of the drawings.

Referring now to the drawings, Figs. 1—3 illustrate a complete fixture which includes the supporting channel of the present invention. This lighting fixture includes a reflector 1, the channel 3, a saddle support 5, starting switches 7, a transformer 9 and the necessary electrical accessories.

Fig. 2 shows the location of the sockets 11 and a tubular lamp 13 therein. The reflector 1 of channel shape may be made of metal, fibre board or Masonite or other suitable materials, preferably enameled. The transformer 9, starting switches 7 and sockets 11 are of the usual

type. The supporting channel 3 is preferably provided with end plates 15 which are bent down to cover and protect the sockets 11.

In order to fasten the channel 3 and reflector 1 together, a key 17 is attached to the channel 3. The attaching member which holds the key 17 in place is preferably a member 19 having a wire receiving recess as shown in Fig. 5. Suitable openings 21 are provided in the Masonite or other reflector in order to receive the key 17. The key 17 is bent as shown at 23 to provide clearance for the central lamp. The key 17 is rotary in the supporting member 19.

The channel member of the present invention 15 is made from a one-piece blank as shown in Fig. 6. The only portion of the blank which is not used in the little corner pieces 25. The blank is preferably first punched with the proper holes, for example, holes 27 for the starter switches if they are employed, arc 29 for ears to be used for chain supports 31, if they are desired, for suspending the channel and the necessary bolt holes 33. In addition, knockout plugs 35 may be almost completely relieved from the sheet for use in attaching the fixture to a ceiling, if this is desired. In lieu of either of the above-mentioned suspending means, a supporting saddle 5 may be substituted as shown in Fig. 1 which rides on the channel itself (see Fig. 5). The 20 bottom edges are bent over as shown at 37 to engage the bottom of the channel.

When installing the fixture the workmen preferably locate the supporting saddle 5 in its desired position on the fixture so as to aline with the support from the ceiling and merely clamp the bent-over portions 37 into firm engagement with the channel 3.

The blank having been punched in the proper places, the segments 39 may be formed to the 40 position shown in Fig. 4 and the ends 15 bent along lines 41. The channel itself is then formed in a single action by means of a die of the proper shape. No holder for the blank is necessary. In this connection it should be noted that no cutting, stretching or lapping is necessary in order to form the channel shown in Fig. 7 from the blank shown in Fig. 6. This is true because the angle between lines 43 and 45 is the same as between lines 47 and 49 in Fig. 4 or see Fig. 1 and Fig. 2.

50 In other words, as the channel bends downward thereby gaining metal, the metal gained is used up by the broadening of the channel.

A typical four-foot supporting channel 3 might have a deep and narrow central portion eighteen 55 inches long, and shallow and wide end portions

fifteen inches long each. Each angle is then 7°, that is, the angle between lines 43 and 45 and the angle between lines 47 and 49 is in each instance 7°.

Unless the portion 39 has already been formed and the end pieces 15 bent at right angles to the remainder of the channel before the channel is formed from the blank, this is done. Ears 51 have been relieved from ends 15 and are bent at right angles to the sides 53. These ears 51 are then welded onto the end members 15.

Ends 15 not only provide protection for the lamp sockets, but also serve as attaching means by which two or more channel members may be attached together to form a lighting unit. Knockout plugs 55 are preferably formed for use in thus attaching a plurality of channels together. Slots 57 may likewise be formed in ends 15 for supporting a diffusing grill, if this is desired.

The reflector 1 not only has the slots 21 cut away but preferably also has notches 59 cut to accommodate ends 15. The notches 59 enable the reflectors of two or more fixtures to fit together snugly when the fixtures are attached together to provide a larger lighting unit.

It will be noted that key 17 is at an angle to the position of reflector 1 when reflector 1 is attached to channel 3. Accordingly, turning key 17 to locate the portion 23 at an angle to opening 21 serves to bring the reflector and channel into close engagement.

From the foregoing it will be clear that the herein disclosed channel support may be easily and quickly formed with relatively inexpensive and simple equipment and at a low material cost. The material itself is utilized economically and only one forming operation is needed. No trimming dies are required and no blank holder is needed on the press. The die press may be of the fast, single action type, because of this.

The unitary construction of the channel herein disclosed provides a rigid support for the fluorescent lamps and the reflector. Although formed of relatively thin sheet metal, the channel 3 is firm and holds the fluorescent lamps 13 rigidly in place.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. In an electric lighting fixture for tubular lamps comprising electrically controlled apparatus for said lamps, a channel integrally formed with a relatively deep and narrow central portion and relatively shallow and wide end portions, the end portion flaring from the central portion on an angle which is the same as the angle at which the narrow portion becomes progressively shallower, a transformer supported in the deep and narrow portion, lamp sockets supported within said channel at the opposite shallow and wide end portions thereof, and means for suspending said channel.

2. An electric lighting fixture for tubular lamps comprising electrically controlled apparatus for said lamps, a channel integrally formed with a relatively deep and narrow central portion on

an angle which is the same as the angle at which the narrow portion becomes progressively shallower, a transformer supported in the deep and narrow portion, lamp sockets supported within

5 said channel at the opposite shallow and wide end portions thereof, means for suspending said channel, a reflector of channel shape having an opening therein, and a key attached to said channel and located to cooperate with said channel, said key being out of perpendicular to the reflector when the reflector is attached to said channel by means of said key and opening to bring the channel and reflector into close engagement.

3. An electric lighting fixture for tubular lamps comprising electrically controlled apparatus for said lamps, a channel integrally formed with a relatively deep and narrow central portion on an angle which is the same as the angle at which

20 the narrow portion becomes progressively shallower, a transformer supported in the deep and narrow portion, lamp sockets supported within said channel at the opposite shallow and wide end portions thereof, means for suspending said

25 channel, a reflector of channel shape having openings therein and rotary keys having operating means attached to said channel and located to cooperate with said openings, said keys being out of perpendicular to the reflector when the

30 reflector is attached to said channel by means of said keys and openings to bring the reflector and channel into close engagement.

4. An electric lighting fixture for tubular lamps comprising electrically controlled apparatus for

35 said lamps, a channel integrally formed with a relatively deep and narrow central portion on an angle which is the same as the angle at which the narrow portion becomes progressively shallower, a transformer supported in the deep and narrow portion, lamp sockets supported within

40 said channel at the opposite shallow and wide end portions thereof, means for suspending said channel, a reflector of channel shape having an opening therein, a key attached to said channel

45 and located to cooperate with said channel, said key being out of perpendicular to the reflector when the reflector is attached to said channel by means of said key and opening to bring the channel and reflector into close engagement, and a

50 supporting saddle for said channel, said saddle having its ends bent in the form of a U to accommodate the edges of said central portion.

5. An electric lighting fixture for tubular lamps comprising electrically controlled apparatus for

55 said lamps, a channel integrally formed with a relatively deep and narrow central portion on an angle which is the same as the angle at which the narrow portion becomes progressively shallower, a transformer supported in the deep and narrow portion, lamp sockets supported within

60 said channel at the opposite shallow and wide end portions thereof, means for suspending said channel, a reflector of channel shape having an opening therein, and a key attached to said channel and located to cooperate with said channel, said key being out of perpendicular to the

65 reflector when the reflector is attached to said channel by means of said key and opening to bring the channel and reflector into close engagement, said channel having portions forming

70 end plates at each end of the fixture adapted to cover and protect the sockets.

EDWIN F. GUTH.
